CALENDAR

Filed April 16, 1928

UNITED STATES PATENT OFFICE.

HUGH FRANKLIN SHEDD, OF MINNEAPOLIS, MINNESOTA.

CALENDAR.

Application filed April 16, 1928. Serial No. 270,444.

This invention relates to improvements in calendars.

An object of the invention is to provide a continuous roll or pad with the days and dates of a particular or current month on one surface, and advertisements or other data and the days and dates of several consecutive months on the reverse surface, whereby the days and dates of a particular month and the advertisements or other data and the days and dates of several consecutive months, will be visible at the same time when the calendar is in use.

A further object of the invention is to provide a calendar pad mounted and arranged to expose in bold type the days and dates of a particular month, and at the same time expose suitable advertising or other data and the days and dates of several consecutive months, with means for conveniently retaining the pad in position, and means for readily turning the pad to expose a succeeding month and data, and means for permitting the tearing off of the free end of the pad after a particular month has passed.

The invention also comprehends improvements in the construction and arrangement of parts which will be hereinafter described and particularly pointed out in the claims.

In the drawing:—

Fig. 1 is a front view of my improved calendar.

Fig. 2 is a vertical central section of same on the line 2—2 of Fig. 1.

Fig. 3 is a detail perspective view of the pad.

Fig. 4 is a detail perspective view of the pad mounting.

Fig. 5 is a detail section on the line 5—5 of Fig. 1.

Fig. 6 is a detail view of a modification.

The numeral 1 indicates a base, formed about mid-way its length with a central transverse opening 2, and near the bottom, said base is formed with a transverse slot 3, parallel with the opening 2.

On the rear of the base, adjacent the side walls of the opening 2, are vertical strips 5—5

reinforced by strips of strong paper 5^a and 50 pasted or otherwise fastened in place. These strips embrace the ends of a shaft 6, and with the back of the base, provide aligned bearings 7—7 for said shaft. The shaft is supported on a flat plate 8, preferably of cardboard, and 55 of such dimensions as to freely rotate in the opening 2. A retaining strip of strong paper 9 overlies the shaft and is pasted to the plate to securely hold the shaft in relation to the plate. 60

The end 10, of a strip of paper 10^a, is fastened to the plate at 11, and is adapted to be wrapped around the plate to form a pad 12. On one surface of this strip of paper is printed in consecutive form the days and dates of 65 the months, from January to December, the width of the printed matter corresponding to a particular month being about equal to the distance between the bottom wall of the opening 2 and the slit 3, as best shown in Fig. 1. 70

On the reverse side of the strip of paper and on opposite sides thereof is printed data representing six months, and advertising or other data intermediate the monthly data. This latter data is printed and arranged to 75 correspond in width and height to the data relating to a particular month on the front surface of the strip. The arrangement on the reverse surface of the strip is repeated throughout the full length of the strip, except of course the arrangement of the calendar data for the months to be exposed to view, and the character of the advertisements differ, so that each time the plate is turned one half revolution, a new combination of 80 monthly data and different advertisements will be presented.

The free end of the wrapped strip of paper 10^a extends from the rear of the plate 8, thence through the opening 2, and down 90 over the face of the base 1, and then through the slit 3.

When the parts described are in assembled form, as shown in Fig. 1, the current month on the front surface of the sheet, is presented in bold type against the base, with the free end hidden in the slit 3, while a portion of the rear surface of the sheet above the ex-

posed front surface, exposes an advertisement or other data and the calendar data for six months more or less.

If it be desired to advance the calendar to expose another month, the end of the sheet 10^a is pulled down through the slit 3, until the plate and the pad rotate one-half revolution. A perforated line 16 is formed in the sheet 10^a between the monthly data, and this 10 is arranged to coincide with the bottom edge of the base. Hence, when the pad is rotated one-half revolution, a perforated line is presented adjacent the edge of the base, and the monthly data pertaining to the month passing 15 can be conveniently torn off.

Obviously, by reinforcing the bearings in which the shaft 6 rotates, sufficient strength is afforded to the calendar to withstand wear and tear incident to the pull on the pad and 20 the friction on the parts as the plate is rotated.

The pad and the arrangement of the data on the reverse surfaces form an important part of the invention, as it is susceptible of 25 being provided with a great variety of data and uses with a base or support other than that shown in the drawing.

It is obvious the printed data on the strip of paper may be so arranged and proportioned 30 that the calendar will show the preceding month, the current month, and the succeeding month. Hence, at a glance, an observer can readily note the dates of three consecutive months, as shown in Fig. 6.

It will also be obvious that in lieu of the 35 data appearing on the reverse surface of the strip, as shown in the drawing, full month data may be substituted, or in lieu of any calendar data at all, the reverse surface may be all advertising.

What I claim is:

1. A calendar, comprising a continuous strip of paper wrapped upon itself to form a pad, one surface of the strip of paper having 45 printed thereon calendar data in consecutive form to indicate the months of a given year and on the opposite surface in spaces corresponding to the spaces on the first named surface advertising or other data, with marginal groups of data representing several respective months, and means for supporting the pad for rotation on its longitudinal axis.

2. A calendar, comprising a base formed 55 with an opening and a slit, a support mounted to rotate in the opening, a pad on the support formed of a continuous strip of paper with its free end extended from the opening and through the slit, the strip of paper having printed on one surface data concerning 60 the days and dates of a particular month exposed between one edge of the opening and the slit, and data on the opposite surface of the strip of paper to be exposed within the opening.

3. A calendar, comprising a base formed

with an opening and a slit, a pad formed of a strip of paper and rotatably mounted in the opening, said strip of paper having consecutive monthly data printed on one surface and other data on the reverse surface, lines of 70 demarkation formed on the strip of paper to separate the consecutive monthly data, the free end of the strip of paper passing through the slit, whereby the strip of paper with a calendar of a month passed may be torn along 75 a line of demarkation with the edge of the base as a guide.

4. A calendar, comprising a base formed with an opening and a slit, strips secured adjacent the end walls of the opening, a reinforcing strip between each of the first mentioned strips and the base, a bar supported between the reinforced strips and the base, a plate supported by the bar to rotate in the opening, and a continuous strip of paper wrapped around the plate and extended through the opening over the front of the base with its free end extended through the slit, and calendar data printed on one surface of the strip and other data printed on the reverse surface of the strip, whereby the calendar data will be exposed between the opening and the slit, and said other data on the reverse surface will be exposed on the pad.

5. A calendar comprising a base formed with a slit, a rotating plate mounted in the base, a strip of paper wrapped on the plate and extended from the plate to and through the slit and serving when drawn upon to rotate the plate, the strip of paper having printed on one surface consecutive monthly data and on the opposite surface other data, the printed data on one surface being arranged to be exposed between the plate and the slit, and the printed data on the other surface being arranged to be exposed in a position overlying the plate.

6. A calendar, comprising a continuous strip of paper wrapped upon itself to form a pad, one surface of the strip of paper having printed thereon calendar data in consecutive form to indicate the months of a given year and on the opposite surface in spaces corresponding to the spaces on the first named surface advertising or other data, and means for supporting the pad for rotation in a fixed plane.

7. A calendar, comprising a continuous strip of paper wrapped upon itself to form a pad, one surface of the strip of paper having printed thereon calendar data in consecutive form to indicate the months of a given year and on the opposite surface in spaces corresponding to the spaces on the first named surface other printed data, and means for supporting the pad for rotation in a fixed plane.

8. A calendar pad mounted for rotation in successive semicycles, said pad including a strip bearing data on each surface, each semicycle rotation of the pad automatically dis-

playing data on the respective sides of the strip.

9. A calendar pad mounted for rotation in successive semicycles, said pad including a strip bearing data on each surface, each semicycle rotation of the pad automatically displaying data on the respective sides of the

strip, the data on one side of the strip being exposed below the pad and the data on the other side of the strip being exposed on the pad.

In testimony whereof I affix my signature.

HUGH FRANKLIN SHEDD.
